WHEEL DRESSING MECHANISM

Conrad L. Ott, Edgar P. Wine, and Harold E. Balsiger, Waynesboro, Pa., assignors to Landis Tool Company, Waynesboro, Pa., a corporation of Pennsylvania

Application August 13, 1929, Serial No. 385,602

3 Claims. (Cl. 125—11)

Our invention relates to a device for dressing or truing the working surface of a grinding wheel.

An object of the invention is to provide means to position the grinding wheel to compensate for reduction in its radius due to the action of the dressing tools and to provide means to actuate the dressing tool and the grinding wheel simultaneously and at the same rate of speed.

A further object is to provide hydraulically operated means for moving the dressing tool across the face of the grinding wheel and to do this automatically.

Referring to the accompanying drawings which are made a part hereof and on which similar reference characters indicate similar parts,

Figure 1 is a partial end elevation of a grinding machine showing our device partially in section,

Figure 2 is a front elevation of the wheel base partially in section, substantially on line 2—2 of Figure 1,

Figure 3 is a sectional plan view of the hydraulic mechanism.

Figure 4 is a view showing more in detail the mounting of the wheel dressing tool.

In the drawings reference character 10 indicates the bed of a grinding machine having a work carriage 11 and a wheel base 12 mounted on a sub-slide 13 on the bed. A grinding wheel 15 is mounted on the wheel base and has a wheel fender 14 mounted adjacent it. A shaft 16 is rotatably mounted in the wheel base and has on its outer end a hand wheel 17 by means of which it may be manually rotated. The shaft 16 has a worm 18 thereon which meshes with a worm wheel 19 on a shaft 20. The other end of the shaft 20 has a beveled pinion 21 thereon which meshes with a corresponding bevel gear 22 on a shaft 23. The lower end of the shaft 23 is machined to form a pinion 24 which meshes with a rack 25 on the sub-slide 13 to move the wheel base toward and from the work. During grinding operations the sub-slide 13 is moved by power mechanism not shown to feed the grinding wheel into the work, such mechanism being well known in machines of this kind. The shaft 16 also has a worm gear 26 which meshes with a worm wheel 27 which wheel is loosely mounted on a shaft 28.

The shaft 28 is screw threaded on its lower end to engage a threaded lug 29 on a slide 30. The slide 30 is mounted in a bracket 31 which is secured to the wheel fender 14. A block 32 carrying a diamond for dressing the wheel is mounted on the slide 30 and is moved by the screw 28 toward and from the grinding wheel. The worm wheel 27 has a cone-shaped depression in its hub engageable by a corresponding cone-shaped clutch 33. As stated the worm wheel 27 is normally rotatably mounted on the shaft 28. When, however, the clutch 33 has been screwed down

until its end engages the worm 27 the worm 27 is then keyed to the shaft 28.

From the description so far given it will be seen that when the clutch 33 is in engagement with the worm wheel 27 rotation of the hand wheel 17 will move the wheel base toward the work and at the same time will rotate the shaft 28 to move a diamond carrying block 32 towards the grinding wheel. The gearing connection is such that the diamond moves a given distance toward the wheel and the wheel moves the same distance toward the work for a given rotation of the hand wheel 17. Thus the amount of material removed from the grinding wheel is exactly compensated by moving the wheel base a similar distance toward the work. The mechanism for moving the pressing tool across the face of a grinding wheel will now be described. A casting 34 is secured to the front side of the wheel base. This casting is provided with bores 35, 36 and 37 to provide for fluid piston 38 reversing valve 39 and plunger 40, respectively. The valve 39 controls admission of fluid from the pressure line 41 to the ports 42 and 43 and exhaust from these ports to the exhaust lines 44 and 45. A throttle valve 46 may be placed in the pressure line 41. It will be clear from the description just given that the position of the piston 38 is determined by the position of the valve 39 with respect to the pressure line 41 and the fluid ports 42 and 43 through which fluid enters the chambers at opposite sides of the piston 38. A piston rod 47 extends outwardly through one end of the bore 35 and is threaded to receive nuts 48 and 49 which may be adjustably spaced apart thereon. The other end 50 of the piston rod extends out through the casing and has the block 32 secured thereon, in which block is carried the dressing tool 62. A nut 63 is screw threaded into the interior of a cup 64 to compress packing 65 therein. A cover plate 66 is secured in the casing 34 by nuts or screws and this cover has a portion 67 around which fits the holder block 32, a key 68 being secured to the portion 67 to prevent rotation of the block. Packing 69 may be secured in place by a plate 70.

The lever 51 is pivoted at 52 and has a lower bent end in which is carried a roller 53. The plunger 40 has a V-shaped outer end engageable by the roller 53. The plunger 40 is backed by a spring 54 seated against a plug 55 screw threaded into one end of the bore 37. The valve 39 has a stem 55, the outer end of which is threaded to receive nuts 56 and 57 which are spaced apart from each other. The lever 51 rests between the nuts 48 and 49, 56 and 57. The purpose of the lever 51 is to operate the valve 39 which controls the admission of fluid to operate the piston 38. A second lever 58 is pivoted also at 52 and has its outer end bent up and engageable by the end of the rod 47. The other end of the lever 58 carries

a roller 59 for engaging the plunger 40 to hold it in retracted position out of engagement by the roller 53. A hook 60 in the lower end of lever 58 has a spring 61 secured thereto, the other end of 5 the spring being secured to the casting 34. The purpose of the spring 61 is to hold the upper end of lever 58 constantly in engagement with the rod 47.

The operation of the device is as follows: During 10 grinding the wheel base 13 is moved toward the work by suitable power means, well-known in machines of this character. The sub-slide 13 always moves against a fixed stop, not shown. To provide for variation in the diameter of the work 15 piece and for wear on the grinding wheel the wheel base is moved on the sub-slide by means of the hand wheel 17 through the gearing which has been described. When the operator wishes to dress the grinding wheel he screws down the 20 clutch 33 to cause it to engage the worm wheel 27, which normally rotates freely on the shaft 28, then as he rotates the hand wheel 17 to feed the wheel in toward the work he also feeds the diamond toward the wheel and the gearing is such 25 that both wheel and diamond move exactly the same distance. The amount of material removed from the grinding wheel is exactly compensated by moving the wheel base a similar distance toward the work. When the wheel base has been 30 moved the desired distance the operator then moves the lever 51 to the left, to shift the reversing valve 39 as shown in Fig. 3, or to the right, as shown in Fig. 2. Pressure fluid enters from port 41 through port 42 to move piston 38 to the 35 right as shown in Figure 3 to start movement of the block 32 carrying the diamond slowly across the face of the grinding wheel. The speed with which the piston moves to the right is determined by the adjustment of the throttle valve 46. As the piston approaches the end of its stroke the nut 48 40 engages the lever 51 and shifts it toward the right. As the roller 53 passes the vertex of the cam on the plunger 40, the plunger shifts the lever further to the right to cut off ports 41 and 42 and to open 45 communication between ports 41 and 43 to admit pressure fluid to the right of the piston, as shown in Figure 3, to start movement of the piston to the left and return the diamond back across the face of the grinding wheel. As the piston reverses and 50 approaches the end of its stroke to the left the rod 47 engages lever 58 and swings it to bring roller 59 against the cam plunger 52 to keep this plunger depressed beyond the reach of roller 53. This prevents reversing of the valve 39 again to 55 move the piston 38 to carry the diamond again across the wheel. When the piston 38 has moved far enough to center the valve it stops and the hydraulic mechanism ceases operation until the lever 51 is again moved to the left by the operator to open communication between the ports 41 and 42 to perform another wheel dressing operation.

If the operator wishes to feed the grinding 60 wheel for grinding purposes without moving the dressing tool the clutch 33 may be disengaged from the worm wheel 27 whereupon rotation of the hand wheel 17 will not affect the position of the diamond holding block 32.

It will be obvious to those skilled in the art 65 that various changes may be made in our device without departing from the spirit of the inven-

tion and therefore we do not limit ourselves to what is shown in the drawings and described in the specification, but only as indicated in the appended claims.

Having thus fully described our invention, what 80 we claim as new and desire to secure by Letters Patent, is:

1. In a grinding machine having a wheel base and a grinding wheel mounted thereon, means 85 for moving the grinding wheel toward and from the work, a bracket mounted on the wheel base, a wheel dressing device mounted on said bracket, means including a disconnectable clutch member for moving the wheel dressing device toward and from the periphery of the grinding wheel to dress 90 the surface of the wheel, said means being operatively connected to the means for moving the grinding wheel toward and from the work in such a manner that the grinding wheel moves toward the work and the dressing device toward 95 the grinding wheel exactly the same distance to compensate for stock removed from the periphery of the grinding wheel by the dressing operation, said wheel dressing device comprising a fluid operated dressing tool and manually controlled 100 means for causing the dressing tool to move one way across the face of the grinding wheel and automatically return to the starting position.

2. In a grinding machine having a wheel base and a grinding wheel mounted thereon, means 105 for moving the grinding wheel toward and from the work, a wheel dressing device, means including a disconnectable clutch member for moving the wheel dressing device toward and from the periphery of the grinding wheel to dress the surface of the wheel, said means being operatively connected to the means for moving the grinding wheel toward and from the work in such a manner that the grinding wheel moves toward the work and the dressing device toward the grinding wheel exactly the same distance to compensate 110 for stock removed from the periphery of the grinding wheel by the dressing operation, said wheel dressing device comprising a fluid operated dressing tool and manually controlled means for 115 causing the dressing tool to move one way across the face of the grinding wheel and automatically return to the starting position, substantially as set forth.

3. In a grinding machine having a wheel base 125 and a grinding wheel mounted thereon, means for dressing the grinding wheel comprising a support movable toward and from the grinding wheel, a fluid motor mounted on said support, said fluid motor being connected to the said wheel dressing 130 means for moving said means in a direction substantially transversely of the plane of the grinding wheel, a valve in control of said motor, a manually operable handle mounted on said support and engageable with a valve stem for shifting said valve to shift the direction of movement of said motor to move the dressing tool in one direction across the face of the grinding wheel, and means movable by a piston of said motor engageable with the said handle for shifting it to reverse said valve to reverse said motor, and means for stopping said motor in its starting position, substantially as set forth.
